POWERIZED FASTENER

James J. Oussani, 777 5th Ave., Brooklyn, N.Y.
Filed Aug. 3, 1960, Ser. No. 47,296
2 Claims. (Cl. 1—106)

This invention relates to a stapling device and is a continuation-in-part of my copending patent application Serial No. 706,519, filed December 31, 1957, now Patent No. 2,957,174, issued Oct. 25, 1960. More particularly, this invention relates to an improved power impelled fastening device for driving fastening elements, such as staples, wherein a conventional stapling machine is secured within a housing provided with an electromagnetic impeller. Still more particularly, this invention relates to an electrically impelled stapling device wherein the driving of a staple is keyed by insertion into the stapling device of the article to be stapled.

Still more particularly, this invention relates to an improved automatic stapling device of the type described in my aforesaid copending application, as well as in my Patent No. 2,403,947 of July 16, 1946.

In the aforesaid patent, there is described an electric staple driving machine having a solenoid impeller which is activated by the closing of a control switch. The control switch, in turn, is closed, as in the present device, by insertion of the work to be stapled, the said switch in the patented device being opened responsive to the movement of means carried by the solenoid armature.

While the patented construction has enjoyed considerable commercial success, it presents certain drawbacks which have been eliminated in the herein-described improved device. Specially, the prior device operated at a noise level found to be objectionable in some applications. Moreover, the said prior device, when subjected to extended periods of heavy use has from time to time required repair and readjustment, particularly as to the synchronization between the deactivation of the impeller and the completion of the stapling stroke. It will be understood that if the impeller is deactivated prior to clinching of the staple in this device, unsatisfactory closing of the staple legs and, accordingly, incomplete fastening will result. Similarly, if the impeller is not deactivated immediately after clinching of the staple is effected, the stapling device is locked by the impeller in the down or driving position against the work and may be removed only after the current supply to the impeller is manually disconnected. As a result, there exists a danger of burning out the impeller coils which are not adapted, in ordinary operation, to carry current continuously for more than very short periods of time.

Efforts to reduce the noise level in the prior construction by interposing a cushion or shock absorbing agent between the impeller and the stapling device have resulted in an aggravation of repair and adjustment problems. The primary cause for such aggravation where cushioning material is used, is the tendency, in time, of such material to become permanently compressed and compacted, thus varying the synchronization between the descent of the impeller and the deactivation of the same.

It is accordingly an object of this invention to provide an improved powerized stapling device of the type described. A further object of this invention is the provision of an improved powerized stapler device having a reduced noise level.

Still a further object of this invention is to provide a powerized fastener device having a decreased operating noise level and improved synchronization characteristics whereby the impeller member is deactivated accurately upon completion of the staple driving stroke, and thereby assures a fully clinched staple.

Still a further object of this invention is to provide an

2

improved stapler device of the type described whereby repair and readjustment are reduced to a minimum.

Still a further object of this invention is to provide a staple driving device wherein staples may be driven a predetermined distance from the edge of the work to be stapled, by the provision of an adjustable impeller actuator control, shiftable longitudinally with respect to the point of application of the staple.

Still a further object of this invention is to provide a staple driving device having the adjustable feature above described wherein accurate synchronization of the deactivation of the impeller with completion of the staple clinching stroke is assured in all adjusted positions of said control.

To attain these objects and such further objects as may appear herein or be hereinafter pointed out, I make reference to the accompanying drawings, in which:

FIGURE 1 is a side elevation of my device with parts broken away to show details of construction;

FIGURE 2 is a magnified vertical section taken on the line 2—2 of FIGURE 1;

FIGURE 3 is a section similar to FIGURE 2 showing the position of the parts upon completion of a staple driving operation;

FIGURE 4 is a side elevational view of the electrical switching control for the impeller assembly, showing the contacts closed by insertion of work to be stapled to start the stapling cycle; and

FIGURE 5 is a view similar to FIGURE 4 showing the contacts open after driving of the staple.

Referring now to the drawings, a housing 10 of cast or sheeted metal or the like is provided with a base 11, separated from the head portion 12 by an open throat 13. The base is preferably provided with suction cups 14 or the like to reduce the transmission of noises incident to operation, as well as to protect the finish of the supporting surface and avoid slippage with respect thereto.

A solenoid 15 is bolted to the housing 10 by bolts 16 passing through U-shaped bracket 17, to which bracket the solenoid 15 is attached. An armature 18 of magnetically responsive material is journaled to move axially within the solenoid 15, the said armature including at its lower end a roller or buffer 19, rotatably secured by pin 20 to the forked bracket member 21 depending from the lower end of the armature or plunger 18.

The plunger 18 is maintained in the raised or normal position shown in FIGURES 1 and 2 by a spiral spring 22, biased at its lower end 23 against the upper leg 24 of the bracket 17, the upper end 25 of said spring 22 bearing against a washer 26 secured to the upper end of said plunger 18.

The housing 10 is provided with a longitudinally extending gauge slot 27, extending substantially parallel to the base 11 of the housing. An electrical control member 30 is slidably secured within the slot 27 by knurled nut 31, the position of said member 30 being adjustable by loosening the nut 31, shifting the control to the desired position with respect to the slot 27, and subsequently tightening the nut 31.

A conventional hand stapling machine 40 is secured in longitudinally extending recess 41 formed in the base 11 of the housing by headless bolt members 42, 42', threadably engaged into laterally extending tapped bores 43, 43', and tightened to bear against the base or pedestal 44 of the machine 40. The stapler 40 includes anvil 45 carried by the pedestal 44 and a driver blade 46 which is activated in the usual manner to drive a staple when the driver arm 47 is depressed. A cushioning pad P of felt, resilient cushioning, rubber, or a combination thereof, is secured to the driver arm 47 by adhesive or a like expedient, the pad being positioned to be interposed in the path of roller 19 on the downward stroke of plunger 18.

The driver arm 47 carries a tripper arm 48 which is adjustably secured to the aforesaid arm by bolts 49, 49 passing through adjustment slots 50, 50 in the arm 48 and threaded into complementary tapped apertures in the said driver arm. The arm 48 is adjustable in a vertical plane and co-acts with the switch or control assembly 30, now to be described.

Except for details to be described, the control assembly 30 is essentially similar to the one described in detail in my Patent No. 2,403,947, issued July 16, 1946, and will be re-described herein only to the extent necessary to understand the present improvement. This assembly is designed to close a pair of switch contacts responsive to the insertion of articles to be stapled to energize the solenoid 15, and upon completion of a staple driving cycle, to de-energize the said solenoid and assure that the same will not be reactivated until after the paper has been withdrawn from the machine and a new article to be stapled inserted in position.

To perform these functions, there is pivotally mounted on the control switch housing 52 a depending actuator arm 53, normally maintained in the forward position (dot and dash lines, FIGURE 4) by spring 54 secured under tension between anchoring point 52a on the switch housing 52 and the said arm 53. A trigger 55 is pivotally secured to the arm 53 and lies in blocking position within the throat portion 13 of the housing.

A pair of metallic contact leaves 56, 57, which are normally separated at their upper and lower ends (as shown in FIGURE 5) are supported from insulated bracket 58b depending from the housing 52. A latch arm 58 of insulating material is pivotally secured to the actuator arm 53 and extends forwardly therefrom through the apertures 59, 60 formed in the leaves 57, 56, respectively. The latch arm 58 includes a rearwardly directed shoulder 61, which shoulder is, in the normal position of the stapler device, engaged over the front face portion 62 of leaf 56 (see FIGURES 2 and 4). A release finger 63 is secured in rearwardly extending position behind the lever 58 and underlies the ledge portion 64 of slide bar 65. Enough of a clearance gap is allowed between the ledge 64 and finger 63 to assure full latch action in all positions of the switch assembly along the arm 48 of the finger 63. The slide bar 65 is mounted on the housing 52, to be vertically shiftable on guide pins 66, 66 which extend through slots 67, 67 of the slide bar 65, a tension spring 68 being secured between the bar 65 and the housing to maintain the slide bar 65 in the "up" position, as shown in FIGURE 4. An abutment finger 69 extends laterally inward from the slide bar 65 to a position beneath the tripper arm 48.

The contacts 70, 71, connected with the leaves 56, 57, respectively, are wired in series with the solenoid 15 and a suitable source of current, so that when the leaves 56, 57 are pressed together, the solenoid is energized, and when separated, the solenoid is de-activated.

When work to be stapled (W) is inserted into the throat 13 of the device, the lever 53 is rocked rearwardly about pivot 53' against the biasing influence of spring 54 by the engagement of said work with the trigger 55. The latching lever 58, which is carried by lever 53, is likewise shifted rearwardly and in turn draws leaf 56 rearwardly into contact with leaf 57 through the medium of shoulder 61 which engages the portion 62 of the said leaf 56. (The two positions of the lever 53 are shown in FIGURE 4 wherein the dot and dash lines show the lever in the normal or "open" position thereof.)

When the leaves 56 and 57 are in contact, the solenoid is energized, causing the roller 19 of plunger 18 to drive against the pad P carried by the driver arm 47 of the stapler. The tripper arm 48 moves with the driver arm to which it is attached, and when the driver arm approaches the clinching position with respect to the anvil 45, said tripper arm 48 engages the abutment 69, causing the slide bar 65 to shift downwardly. The downward

movement of the slide bar 65 causes the ledge 64 carried by the slide bar to strike the release finger 63 of the latching lever 58, pivoting the latter in a clockwise direction, as shown in FIGURE 4, about the horizontal axis 5 provided by pin 58', to the position shown in FIGURE 5. In pivoting from the position of FIGURE 4 to that of FIGURE 5, the shoulder 61 is raised to clear the portion 62 of leaf 56 and the released leaf 56 springs back out of engagement with leaf 57 to the position shown in FIGURE 5, breaking the circuit to the solenoid.

It will be noted that so long as the lever 53 is maintained in rearward position by contact with the work W, the circuit cannot again be activated, since leaf 56 can be re-engaged by latching lever 58 only by permitting the lever 53 to return to the forward position (dot and dash lines, FIG. 4) and such forward position can be attained only after the work is withdrawn from contact with trigger 55.

After a staple has been driven, the stapler device 40 and plunger 18 return to the original "up" position shown in FIGURE 1, and the tripper arm 48 releases the slide bar 65, permitting the latter to move vertically under the influence of spring 68. The release finger 63 is, upon upward return movement of slide bar 65, released from engagement with ledge portion 64, thus allowing the lever 58 to pivot counterclockwise about the pin 58' under the influence of gravity, and when the lever 53 is returned to its forward position, the shoulder 61 of lever 58 again will engage the portion 62 of leaf 56 in position to reactivate the solenoid upon insertion of work.

From the foregoing description of operation, it will be readily recognized that successful operation is dependent upon accurately timing the clinching of the staple with the de-activation of the solenoid 15. Thus, if the solenoid is de-activated prior to clinching of the staple by premature depression of abutment finger 69 by tripper arm 48, the legs of the staple will not be fully closed, and tardy tripping of abutment finger 69 may result in jamming and solenoid burnout, as earlier described. As best seen in FIGURE 1, the tripper arm 48 is angularly oriented with respect to the base 11 in the "up" position of the solenoid, but assumes a parallel relation to said base in the clinching position of the stapler. This arrangement assures that power to the solenoid will be cut off at the same point regardless of the position of control member 30 with respect to the slot 27.

The interposition of a noise reducing buffer between the plunger and the stapler of the structure of my previously mentioned Patent No. 2,403,947 was found to aggravate considerably the timing or synchronization problem aforesaid, since all materials which might effectively serve as buffers tended to become compacted after even moderate use. Such compaction seriously disrupts the timing of the de-activation of the impeller member since, upon increasing compaction, the tripping of the abutment finger occurs progressively earlier during the stapling cycle, i.e. prior to full clinching.

I have discovered that accurate timing is maintained in the above described structure notwithstanding the use of a compactible buffer, by mounting the tripper arm 48 on the driver arm 47 of the stapler rather than having the tripper move with the solenoid armature, as is the case with the structure of my said prior patent.

There are, in addition, other unobvious advantages in the instant stapler device. Since the tripper is no longer connected to the solenoid armature, the armature and solenoid in my present device need not be machined as accurately as was previously required. Also, in the prior device, tripping of the abutment by an arm carried by the solenoid set up considerable torque in the arm and applied a sidewise force to the armature as it slid by the solenoid, thus causing excessive wear. Such torque and wear are virtually eliminated in the present device by mounting the tripper arm on the driver arm of the stapler.

It will be recognized that the slotted apertures 50, 50 in the tripper arm 48 enable the position of said arm to be adjusted relatively to the driver arm 47 by the expedient of loosening bolts 49, 49 and re-tightening the same when the arm 48 is adjusted as desired. Such upward or downward movement of arm 48 affects the timing of de-activation of the solenoid and may be used, if necessary, to adjust the stapler device for special situations where unusually thick or thin work is to be fastened. Thus the arm 48 should be lowered with respect to driver arm 47 where unusually thick work is to be encountered, the opposite procedure being followed where thin work exclusively is to be used.

The use of a buffer or noise deadener greatly adds to the attractiveness of the stapling device, since in prior unpadded devices the stapling operation was accompanied by a loud report when the lower portion of the plunger struck the stapler member.

Having thus described my invention and illustrated its use, what I claim is new and desire to secure by Letters Patent is:

1. An electrically operated fastener comprising a housing, a stapling device secured in said housing and including an anvil, and a staple driver arm vertically movable

relative thereto, electrically powered means secured to said housing and including an impeller member shiftable toward and away from said driver arm, a compressible cushion member interposed between said driver arm and said impeller in the path of movement of said impeller, switch means carried by said housing including a laterally extending abutment, said switch means having a single pair of contacts adapted to be closed by insertion of articles to be fastened and released to open position by depression of said abutment, and a longitudinally extending tripper arm affixed to said driver arm to lie in the path of movement of said abutment, said arm being shifted into depressing engagement against said abutment when said driver arm is impelled to a predetermined distance from said anvil.

10 2. A device in accordance with claim 1 wherein said tripper arm is adjustably secured to said driver arm to permit relative movement of said parts in a vertical plane.
